UNITED STATES PATENT OFFICE.

HARRY W. CROOKER, OF BOSTON, MASSACHUSETTS.

WELT SHOE.

Application filed February 20, 1925. Serial No. 10,470.

To all whom it may concern:

Be it known that I, HARRY W. CROOKER, a citizen of the United States, residing at Boston, in the county of Suffolk and State of Massachusetts, have invented certain new and useful Improvements in Welt Shoes, of which the following is a specification.

This invention relates to boots and shoes designed for the corrective treatment of the foot and more particularly to the manufacture of welt shoes having an insole adapted to the relief of such infirmities as require special support of the metatarsal and longitudinal arches of the foot. Accordingly the invention comprehends a novel welt insole and the boot or shoe having such insole as a feature.

It is a particular object of the present invention to produce a shoe which may be worn with relief by persons having such foot infirmities as metatarsalgia and the like, due to weakness of the transverse arch of the foot; but which is so constructed that relief may also be obtained from pes planus, due to weakness of the longitudinal arch, popularly known as "flat-foot". Frequently the same patient requires correction for both infirmities and this is provided for by the present invention.

With this object in view an important feature of the invention contemplates a type of shoe having provision for the relief of one or more of the infirmities referred to, as may be requisite in any particular case, without change in its design. This is accomplished by building into the shoe an insole so constructed that the salesman in the shoe store may manipulate it and combine with it such corrective elements as may be necessary to suit the particular requirements of the prospective purchaser.

More particularly a pocket is provided in the insole having a mouth, readily accessible after the shoe has been built, and into which a pad, arch support or other corrective element may be thrust as may be required. The size of the pocket is such that the remedial pad or other support may be correctly positioned to relieve the particular infirmity of the wearer of the shoe, and the proper longitudinal location of the corrective element is determined by a definite limitation of the forward end of the pocket.

To the accomplishment of the above object and such others as may hereinafter appear,

as will be understood from the following description by those skilled in the art, the invention comprises the features and combination of parts hereinafter described and then particularly pointed out in the appended claims.

The preferred form of the invention is illustrated in the accompanying drawing in which,

Fig. 1 is a view of the novel shoe, in cross section, with a remedial pad associated with the insole. This view is taken on a plane that would pass through the metatarsal pocket of a left foot.

Fig. 2 represents a cross section through the shank of the novel shoe, the mouth of the remedial pad pocket being shown opened by lifting the entire heel and shank portion of the sock face insole layer from the under layer.

Fig. 3 is a view of the rib side of one type of insole (that for a left shoe being shown) that may be employed, the curved dotted line indicating dry-thread stitching which forms the forward limitation of a pocket for receiving the remedial pads. In this view a remedial pad and a steel shank are both shown within the insole by a dotted line, but they may be used independently each of the other.

Fig. 4 is a perspective view showing the grain side, or sock face of the insole shown in Fig. 2. In this view another type of remedial pad is shown within the pocket bounded forwardly by the dry-thread stitching.

Figs. 5 and 6 are views, in cross section, through the shank of the type of insole shown by Fig. 3, illustrating certain steps of its manufacture, and

Fig. 7 is a perspective view of one type of remedial pad.

In the embodiment of the invention illustrated in the drawing the Goodyear welt type of shoe is shown having incorporated therein a reinforced insole of the Economy type, and this type of sole will be utilized to explain the nature and purpose of the invention. Those skilled in the art will recognize, however, that the novel features of the invention may be embodied in Goodyear welt shoes having other types of reinforced, manufactured or other laminated insoles.

The novel insole will be described first,

and then its manner of incorporation in the shoe will be explained, providing for its manipulation in the completed shoe to transform an ordinary shoe into a shoe for 5 correcting such infirmities as have been referred to.

Referring first to Fig. 3 which, in certain particulars, illustrates the ribbed side of a completed Economy type insole, such as is 10 disclosed in Letters Patent of the United States to Albert E. Johnson, No. 849,245, dated April 2, 1907, it will be observed that the body 10 of the insole is provided with a marginal rib 12 throughout the shank and 15 fore part as is requisite in the manufacture of Goodyear welt shoes. The blank is fitted by producing a marginal lip 14 and a parallel marginal channel flap 16 joined at their bases to the between-substance 15. The 20 lip and flap in the usual process of manufacture are then raised, cemented together and finally reinforced by the application of a sheet of reinforcing material 20, such as cotton duck, to the ribbed face of the insole.

25 In the present instance, before the lip-turning and reinforcing operations occur, the insole is split from the heel end toward the toe to a point forward of the ball line, as shown best by Fig. 4. This operation may 30 conveniently be performed with a band-knife well known in the art for such purposes. Care is taken to feed the insole to the band-knife in such a plane that the slit 22 (Fig. 5) will produce an upper layer 24 35 somewhat heavier (of greater thickness) than the under or ribbed layer 26. The upper layer 24 is the grain side of the insole and forms the sock surface when built into a shoe. It also forms the "roof" of the 40 metatarsal pocket 21 that forms the important feature of this invention. For these reasons it should be as strong as possible to provide for wear and afford protection. At the same time the slit 22 must be in a plane 45 below (Figs. 5 and 6) the between-substance 15 so as to provide a feather 17 of adequate strength to support the welt 19. This is highly important because if the feather is too thin, or if the slit is made in the plane 50 of the between-substance, the shoe will quickly lose its shape. The feather is a highly important part of a welt insole and by splitting at 22, as shown by Figs. 5 and 6, the advantages hereinafter described may 55 be secured while yet preserving all the advantages of a well made Goodyear welt shoe. The fact that each layer is of the full width of the insole is an important factor on shape insurance.

60 The forward end of the slit 22 is indicated by the transverse dotted line 28 on Figs. 3 and 4. This is somewhat forward of the ball line so as to provide for an insole pocket between the two layers that extends beneath 65 the metatarsal arch of the foot. In order to

prevent enlargement of the pocket 21 by a further splitting apart of the layers 24 and 26, under the strains placed on the shoe while in use, and also in order to definitely determine the forward limitations, or boundary of the pocket, the two layers are secured together adjacent the fore end of the slit 22. This securing comprises a line of dry-thread stitching 30 through both layers, applied either before or after reinforcing as may be deemed desirable, that extends in a curve across the insole and rearward in the channel for a short distance (see Fig. 3), but not into the shank of the insole, leaving the two layers wholly unso connected at both margins throughout the shank and heel-seat. The stitching 30 follows generally the forward-ends of the bones of the metatarsal arch of the foot and forms the forward limitation of a pocket to the rear thereof that underlies the entire metatarsal area. Beside affording a definite boundary at the forward end of the pocket 21, the stitching effectually prevents further splitting of the insole at the forward end of the slit 22 when the insole is severely flexed back and forth, in walking.

The formation of the insole having been completed, as explained, it is incorporated in the shoe in the usual manner. Upper materials 18 are lasted in over the feather 17. The welt 19 is inseamed to the sewing-rib 12, cork or other filling 23 is applied if necessary, and an outsole 25 is stitched to the welt 19 (Fig. 1).

During the process of assembling the insole and upper on the last a thin heel-plate 31 of steel, or other suitable metal, is inserted between the two layers 24 and 26 at the heel-seat, as indicated by Fig. 4, and this heel-plate remains in this position during the remainder of the shoemaking process including the heel-attaching operation. In lasting the upper at the heel the points of the lasting tacks are clenched on the plate 31 against the inner surface of the insole layer 26. In the heel-seat nailing and heel-attaching operations the points of the attaching nails are clenched in like manner against the inner surface of the insole layer 26. The heel-plate 31 may be removed after the heel is attached, the unsecured sock layer 24 of the insole being lifted from the under layer 26 for this purpose. At this time, or later, a heel pad, which may be a usual piece of felt, is cemented on the heel-seat of the under insole layer 26 over the exposed clenched ends of the insole layers and heel nails. This produces the custom-made machine-made-shoe heel-seat and when the upper insole layer 24 is again laid down on the under layer 26 its smooth, unmarred surface provides a fine custom-built-shoe heel-seat. It is particularly pointed out that in the completed shoe the upper or sock 100

layer 24 of the insole is wholly unconnected to the under layer 26 rearward from the ends of the stitching 30, that defines the forward end of the metatarsal pocket 21, throughout the entire shank and heel-seat.

The under layer 26 is firmly held to the outsole by the inseam and outseam but, due to the construction just described, the entire rear portion of the upper layer 24 may be freely lifted therefrom at will. By reaching into the completed shoe and starting at the inner side of the shank where there is more room to insert the fingers between the two layers (see Fig. 2), the upper layer of the insole may quickly be drawn up and curled forward into the lacing slit of a bal shoe, or over the vamp of an oxford or pump, (see dot and dash lines on Fig. 4), thus exposing the metatarsal pocket 21 and permitting an easy insertion of a remedial pad in such position as may be desirable for the cure of a particular foot infirmity, as will now be described. When the insole layer 24 is laid back upon the under layer 26, after completing a pad insertion, its material thickness acts to mold the pad to the rounded shape (Fig. 1) that affords the greatest comfort to the wearer of the shoe.

Infirmities of the foot may be placed in two general groups, those due to a weakness of the metatarsal arch and those due to a weakness of the longitudinal arch. The manner in which the insole is manipulated to correct some of the foot infirmities resulting from such weak arches will now be described.

"Morton toe," a form of metatarsalgia, is a condition resulting from the fourth metatarsal dropping to a lower plane than is normal for this bone, causing painful pressure on one or more of the plantar nerves. Relief from this pressure may be obtained by a wedge under the extreme outer side of the metatarsal pocket supporting the fourth metatarsal at a point back of the forward ends or heads of the three central bones which form this pocket. Accordingly a pad 32 having the characteristic form shown by Fig. 7 is inserted in the pocket 21 through its opened mouth and then positioned as shown by dotted lines on Fig. 4 at the outer edge of the metatarsal pocket, with a pointed end forward under the weakened bone so that this bone is raised and supported in its correct relation to the other bones of the metatarsal arch.

Metatarsalgia is the result of weakened muscles and ligaments that allow the second, third and fourth metatarsals to drop into a lower plane than the first and fifth. This also causes painful pressure on one or more of the plantar nerves which is relieved only by restoring the metatarsal arch to its natural formation. In correcting this infirmity, a remedial pad 34, of the form shown by

dotted lines in Fig. 3, is inserted in the pocket 21 and placed centrally thereof, or below the central portion of the metatarsal pocket, thus supporting and restoring the arch.

Pes planus is the well known "flat-foot" and involves a breaking down of the longitudinal arch of the foot due to weakness of the muscles and ligaments. This condition may be relieved by placing a light, steel shank 36, indicated by dotted lines in Fig. 3, under the central portion of this arch. Such a shank may readily be inserted in the proper location in the rear portion of the pocket 21 and then tacked in place.

The above explanation will indicate the manner in which various foot infirmities are corrected or relieved by means of the present invention, it being understood that the particular infirmities described are only by way of example. Attention is called especially to the size of the pocket 21 i. e., the considerable area of the face of the insole body over which it extends. This construction provides a single insole pocket which may be utilized for the reception of the different remedial elements for the correction of all known foot infirmities, with the advantage that a special insole need not be constructed for correcting each infirmity. Attention is especially called to the fact that all this provision is made in a regular insole adapted to be incorporated in the shoe during its manufacture, and so constructed that it can be utilized for this purpose after it has been made a part of the shoe. Having the shoe with the novel insole built into it, it only remains to select the proper corrective element and then position it correctly within the pocket. The stitching 30 effectually prevents the remedial pad from creeping forward and then becoming misplaced, and the size of the pocket permits ample adjustment to suit the form of the wearer's foot, which may have short toes and a long arch or vice versa. The nature and construction of the pads may be varied as becomes desirable. In practice excellent results have been obtained with pads formed from crêpe rubber and from felt.

Those skilled in the art will recognize the extreme simplicity of the insole construction for producing a metatarsal pocket of sufficient area, in the proper location, and covered or roofed by an adequate thickness of insole stock. The two insole layers are never cemented together and access to the pocket for insertion of a remedial pad requires no greater effort than a mere separation of these layers. The equal width and substantially equal thickness of the two layers, together with their free margins at both sides, facilitates the work of pad insertion. Obviously an unreinforced welt insole may be employed if desired, and the inven-

tion is not to be limited to any special feature of the illustrated embodiment except as specified in the appended claims.

The nature and scope of the invention 5 having been indicated and the preferred construction of the insole, the shoe, and the process of their manufacture having been specifically described, what is claimed as new, is:—

- 10 1. A welt shoe, of the type having a metatarsal pocket for holding a remedial pad, comprising: an insole having a welt-attaching rib throughout the shank and fore part and split in a plane above the base of said rib, throughout the shank and to a point forward of the ball-line forming upper and under layers separable throughout the shank and heel-seat but integrally connected at the fore end of the fore part, and further connected at the fore end of the split by a line of stitching extending in a curve transversely across the insole, following generally the forward ends of the bones of the metatarsal arch of the foot, thereby forming a 15 pocket adapted to hold said remedial pad, access to the pocket being obtained by lifting the rear portion of the upper layer from the lower layer; upper materials and a welt secured to said rib on the under layer; an 20 outsole secured to said welt and to said under layer only at its heel end; and a heel secured to the outsole and said connected insole layer.
- 25 2. A welt shoe, of the type having a metatarsal pocket holding a remedial pad, comprising: a ribbed insole having a construc-

tion that provides two separable layers at the heel-seat, shank and through the fore part to a point forward of the ball-line, said layers being of equal width at the shank 40 and being connected forward of the ball-line by a line of stitching extending in a curve transversely across the insole, following generally the forward ends of the bones of the metatarsal arch of the foot, thereby 45 forming a pocket adapted to hold said remedial pad, access to the pocket for inserting said pad being obtained by separating the layers throughout the heel-seat and shank; upper materials and a welt secured 50 to said rib; an outsole secured to said welt and to the adjacent insole layer at its heel end; and a heel secured to the outsole and said connected insole layer.

3. The method of making welt shoes which 55 comprises preparing an insole by channeling and lip-turning to form a sewing rib, by splitting from its heel end to a point forward of the ball-line in a plane intermediate the base of the rib and its unribbed face and 60 by securing together the two layers thus produced by a transverse line of stitching at the fore end of said split; inserting a metal heel-plate between said layers; assembling said insole with an upper on a 65 last; lasting, welting, outsole attaching and heel attaching with said heel-plate in place; and thereafter removing said heel-plate leaving said two insole layers separate and unsecured to each other rearward from said 70 transverse stitching to the heel ends thereof.

HARRY W. CROOKER.
